UNITED STATES PATENT OFFICE.

GEORGES H. MORAEL, OF ST. PETERSBURG, FLORIDA.

ASSEMBLER-CHUTE BUFFER.

Application filed April 16, 1926. Serial No. 102,558.

My invention aims to provide a mechanism to take the place of the assembler chute spring on typesetting machines such as linotypes, intertypes or linographs, which will permit 5 a greater assembling speed, prevent transposition, and be readily adjustable for different working speeds and for matrices of different sizes and weights.

One object of the invention is to avoid the 10 use of springs, thereby giving a smoother action, a readier and more accurate adjustment, and reducing the liability of breakage.

Further objects and advantages will be apparent to those skilled in the art from the 15 following description, and accompanying drawings of a preferred embodiment illustrative of my invention. It is to be understood that the principles of my invention may be applied in other forms and to other machines than the one herein shown and described, which illustrates one mode of application to a typesetting machine of well known make.

The preferred form of mechanism whereby 20 my objects are attained is shown in the accompanying drawings, wherein:

Fig. 1 is a side view of the assembler chute buffer applied to a typesetting machine, only enough of the latter being shown to make 25 the relation evident;

Fig. 2 is a perspective view of the complete buffer; and

Fig. 3 is an end view looking in the direction of the arrows 3—3 of Fig. 1.

35 My buffer may be used to replace the assembler chute springs on existing typesetting machines, or be installed as an original part of new machines. Its relationship to the other parts of the machine is apparent 40 from Fig. 1, which shows diagrammatically the matrix chute 11, including the usual belt 12, wheel 13, and guide plates 14, together with the spacer band chute 15. The star wheel 16 passes the matrices and space bands 45 from their respective chutes to the assembling elevator 17, as is well understood in machines of this type of construction.

The complete buffer comprises an outer throat plate 20 and an inner throat plate 21, 50 attached to a support 22 preferably by a hinge (Figs. 2 and 3) comprising a series of pairs of overlapping perforated ears, 23, 24, and 25, one pair being formed on each of the three principal members of the buffer, 55 pivotally joined by a horizontal pin 26, passing through the perforations.

The support 22, which may conveniently be stamped from a single piece of sheet metal, consists of a vertical strip constituting a base, and having a bracket 27 at its 60 lower end. The vertical strip, which stands in a plane perpendicular to the throat plates, is slotted at 22^a for ready attachment to the machine frame and for adjustment thereon, being held in place by a large headed screw 22^b, or like means. The bracket projects outwardly and to the right (see Fig. 1) beyond the vertical strip, and this projecting portion has the pair of downstruck ears 23 which are the interior pair of 65 the series forming the hinge and which are perforated to receive the hinge pin 26. The support may be in any other shape which will serve the purpose of holding the throat plates in operative relation to the other elements of the typesetting machine and permit necessary adjustments.

The outer throat plate 20 consists of a flat strip disposed transversely to the matrix chute, and whose working face is of uniform width slightly narrower than that of the chute, sharply bent into three sections forming a rigid unit. The upper section 28, which stands approximately vertical, carries near its top a substantially horizontal 70 forwardly extending threaded stud 29 on which an internally threaded counterweight 30 is adjustably mounted. The central section which is approximately horizontal, supports the plate 20 by means of the upstruck 75 perforated ears 24 fitting outside the ears 23 of the bracket 22, and swingingly supported by pin 26. The lower section, which is forwardly and downwardly inclined, terminates in a broad pointed tongue 31, of such 80 shape and size as to engage with the usual V-slot in the top of each descending matrix, to straighten and guide the matrices in their downward course, as will be readily understood by those skilled in the art. This lower 85 section also includes two forwardly projecting parallel flat prongs 32 perpendicular to the main portion of the throat plate at opposite sides, near the lower end thereof, spaced apart sufficiently to allow space bands 90 dropping out of the chute 15 to pass between them in the usual manner.

The inner throat plate 21 is a strip substantially as wide as and somewhat shorter than the outer plate, reversely curved, cut 95 square across at top and bottom, but with slightly tapered top corners. It hangs below

the outer plate 20 by the long narrow perforated upstruck ears 25, near the top, which ears receive the horizontal pin 26, and embrace the ears 24 on the outer throat plate. 5 The short portion of this inner plate above the ears is upwardly curved at 33 while the longer lower portion is downwardly curved toward the matrix guide 14. This plate 21 has a restricted capacity for oscillation free

10 of the outer throat plate 20, this free oscillation being limited rearwardly by contact of the upper end 33 with the central section of the outer plate, and forwardly by engagement of the lower ends of the two plates.

15 Since both throat plates are suspended by a common pivot 26, it is obvious that they will be constrained to swing together when beyond the range of independent oscillation.

Both throat plates are so hung on the pivot 20 26 that their own weight impels their lower ends toward the matrix guide, thus making it necessary for matrices passing down the chute to push the plates aside forwardly. The counterweight 30 is so placed as always 25 to add to this turning moment, thus increasing the resistance to the passage of matrices down the chute. This additional moment will be greater or less according to the setting of the counterweight. Thus when using 30 large heavy matrices the counterweight will be set to the left as seen in Fig. 1, increasing the lever arm about the pivot 26, so adding to the resistance. Conversely, for lighter 35 matrices the counterweight will be set further to the right. Should a still greater range of adjustment be desired, a heavier counterweight, or a plurality of such weights, might be used. On the other hand the 40 counterweight can be removed entirely, or a lighter one substituted, all according to conditions, without affecting the principles of 45 operation on which my invention rests.

In the operation of a typesetting machine equipped with my buffer, a matrix passing 45 down the chute 11 and over the guide 14 will push up the inner throat plate 21 to the limit of its free movement, and then the outer plate 20 also, since the plates normally hang close to the chute with their lower ends apart. 50 The resistance encountered will retard the speed of the matrix. The inner plate being shorter than the outer and capable of some free swing in both directions, drops back towards the guide 14 after the matrix passes 55 and while the outer plate 20 is still pushed up, thus taking a position where it will positively prevent the matrix below from jumping up and back, and where it will also retard the next downcoming matrix, which, in rapid 60 work, may arrive before the first matrix has passed the outer plate, and consequently before the outer plate has had time to drop back towards the guide.

After the matrix has dropped below the 65 inner plate 21, the sides of its V groove en-

gage, in passing, the sides of the tongue 31, thus insuring transverse adjustment. The prongs 32 next press the matrix down by its shoulders in the usual way into a vertical position and into contact with the star wheel 16, to be moved into the assembling elevator 17. This movement also serves to return the outer plate 20 into place near the matrix 70 guide.

This feature of having the inner plate 75 quickly return to a retarding position, where it may also have some movement independent of the outer plate, is of great importance, since it prevents "stunning", which might otherwise occur in rapid work. By "stunning" I mean stopping of a descending matrix, which results in causing subsequent matrices to pile up, thus choking the throat. "Stunning" is often caused by a returning assembler chute spring striking a downcoming 80 matrix. "Stunning" and choking may also result from a second matrix striking the preceding one while the preceding one is still holding the chute spring up. This also is prevented by my partially independent inner throat plate 21.

Choking, "stunning" and other irregularities may also be due to a gradual weakening of an assembler chute spring with age and wear, which I avoid by gravity actuation. 85

The space bands drop from the chute 15, between the prongs 32, as with existing assembler chute springs.

The spacing of the lower ends of both 90 throat plates 20 and 21 from the matrix guide 14 is adjusted by moving the support 22 up or down on the slot 22^a and screw 22^b. Thus the distance between the lower end 31 of the outer plate and the guide 14 may be adjusted 95 by moving the counterweight. 100

It will be understood that such modifications in dimensions, weights, and other features of construction and design, as may be necessary to adapt my apparatus to different 110 styles of typesetting machines and to operation with matrices and space bands of various forms, sizes and weights, may be made without departing from the spirit and principles 115 of my invention.

What I claim is:

1. A gravity-actuated assembler chute buffer having a counterweighted outer throat plate, a horizontal pivot supporting said plate in such manner as to permit said plate to swing in a vertical plane, and an inner 120 throat plate also supported upon said pivot in such manner as to be capable of swinging under the influence of its own weight independently of, but through an arc limited by, said outer throat plate. 125

2. A gravity-actuated assembler chute buffer comprising, in combination, a support for attachment in operative relation to a typesetting machine, two throat plates supported by a common pivot for limited inde- 130

pendent movement and for greater coincident movement, a counterweight so placed as to influence all movements of one of said throat plates, and to influence the coincident movements of both of said throat plates.

3. An assembler chute buffer comprising in combination, a support, a gravity-actuated throat plate hinged to said support, a counterweight carried by said throat plate, a 10 downwardly projecting matrix guiding tongue on the lower end of said throat plate, and forwardly projecting matrix engaging prongs near the lower end of said throat plate.

15 4. A gravity-actuated assembler chute buffer having a counterweighted outer throat plate, a pivot supporting said plate to permit said plate to swing, and an inner throat plate supported upon a pivot in such manner 20 as to be capable of swinging under the influence of its own weight independently of, but through an arc limited by, said outer throat plate.

5. In an assembler chute buffer, the combination of gravity-actuated inner and outer throat plates having a common pivot, said outer throat plate being provided with forwardly projecting matrix-engaging prongs near its lower end.

30 6. A gravity-actuated, pivoted assembler chute buffer, having an inner throat plate and an outer throat plate, adapted to be placed in operative juxtaposition to matrix-guiding means, said outer throat plate having 35 a lower end adapted, when in a position of repose, to be further spaced from said matrix-

guiding means than is the lower end of said inner throat plate, said inner throat plate adapted to oppose passage of matrices along said guiding means by a light constant force 40 acting through a relatively restricted arc, said outer throat plate adapted to move in common with said inner throat plate beyond said restricted arc, whereby to oppose passage of matrices by increased constant force. 45

7. A gravity-actuated assembler chute buffer, having inner and outer throat plates, said throat plates oscillatably mounted on a common pivot, said inner throat plate capable of limited oscillation independent of said outer throat plate and capable of a greater oscillation in common with said outer throat plate, the lower end of said inner throat plate being inwardly spaced from the lower end 50 of said outer throat plate. 55

8. In an assembler chute buffer in combination with a matrix-guide, a relatively light gravity-actuated matrix-retarding member close to said guide, and a relative heavy gravity-actuated matrix-retarding member 60 spaced further from said guide, mounted for occasional partial coaction with said relatively light member.

9. In an assembler chute buffer, a matrix guiding tongue and prongs pivotally mounted for engagement by and oscillation in common with independent matrix-retarding means. 65

In testimony whereof, I have signed my name to this specification.

GEORGES H. MORAEL.
